CURRENT TRANSFORMER

Franz Joseph Fischer, Dresden-Mickten, Germany, assignor to Koch & Sterzel Aktiengesellschaft, Dresden, Germany

Application June 10, 1933, Serial No. 675,205
In Germany June 10, 1932

4 Claims. (Cl. 175—358)

This invention relates to current transformers and refers more particularly to so-called spreader current transformers provided with a pot-shaped insulating body.

5 Current transformers known in prior art are comparatively high and bulky in size. In order to eliminate this drawback it has been proposed to construct transformers comprising two or more insulating bodies which are arranged side by side 10 in stepped formation. This construction however was found to be unsatisfactory.

An object of this invention is the provision of current transformers which have a comparatively 15 low height and which at the same time are inexpensive and convenient to manufacture and are efficient in operation. The above and other objects of the present invention may be realized through the provision of current transformers which comprise a plurality of super-imposed insulating bodies, said insulating bodies having 20 portions which are situated side by side when the transformers are assembled.

The invention will appear more clearly from the following detailed description when taken in 25 connection with the accompanying drawings showing by way of example preferred embodiments of the inventive idea.

In the drawings:

Figure 1 is a section through a portion of a 30 transformer constructed in accordance with the principles of the present invention, and illustrates diagrammatically the adjacent portions of two insulating bodies of the transformer and the windings carried by these portions.

35 Figure 1a shows in perspective the two insulating bodies which, when assembled, constitute the body of the transformer shown in Figure 1.

Figures 2, 3 and 4 are vertical sections through 40 differently constructed transformers.

Figures 5 illustrates a transformer provided with means for increasing the stability thereof.

Figure 6 is a section along the line 6—6 of Figure 5.

Figure 7 shows a transformer of a somewhat 45 different construction.

Figure 8 illustrates diagrammatically a transformer provided with a switch.

The transformer illustrated in Figures 1 and 50 1a of the drawings comprises two separate hollow insulating bodies 20 and 21. In Figure 1, the insulating body 20 is shown as being placed on top of the insulating body 21. In Figure 1a the two insulating bodies are shown in perspective separately from each other, but it is illustrated in that figure that the insulating body 20

may be placed conveniently upon the insulating body 21.

The insulating bodies 20 and 21 are hollow. A rectangular tube 12 is situated within the interior of the hollow insulating body 20 and constitutes an integral part of that body. The interior of the tube 12 is designated by the numeral 13 in the drawings.

The hollow insulating body 21 is provided with a similar tube 18, which is situated within the insulating body 21 and forms an integral part of this body. The interior of the tube 18 is designated by the numeral 17 in the drawings.

As shown in Figure 1a, the adjacent portions of the insulating bodies 20 and 21 have the shape of 15 steps which are adapted to be placed one over the other in such manner that the surface 22 of the insulating body 20 is situated over the tube 18, constituting a part of the body 21. When the insulating body 20 is placed over the insulating 20 body 21 in this manner, the surface 23 of the insulating body 21 is situated underneath the tube 12 of the insulating body 20. This position is shown in Figure 1 of the drawings. In this position, the passages 17 and 13 of the two insulating bodies are in alignment with each other, forming a single continuous passage having a common central axis. In this assembled position, the tubes 18 and 12 are situated opposite each other and each one of them forms a continuation 30 of the other.

The tube 12 of the insulating body 20 serves as a support for the primary winding 11 which is wound in coils around the tube 12 as shown in Figure 1. The terminals 11a and 11b of the 35 primary winding 11 may be connected to any suitable source of electrical energy not shown in the drawings.

The tube 18 of the insulating body 21 serves as a carrier for the secondary winding 19 which 40 is wound around the tube 18.

In the example illustrated in the drawings, the two ends of the secondary winding 19 are connected to a measuring instrument 19a.

An iron core 14 is situated within the passages 45 17 and 13 formed by the aligned tubes 18 and 12. Any suitable means not shown in the drawings may be used for supporting the iron core 14 within the passages 17 and 13. In actual practice the core 14 fills out the passages practically entirely.

The core 14 carries a winding 15 which is wound practically around the entire core. As shown in Figure 1, the two ends of the coil 15 are joined together so that this coil constitutes an entirely 55

separate closed electrical circuit. The only current passing through the coil 15 is that induced by the electric and magnetic field produced by the coil 11. The purpose of the coil 15 is to transmit power from the primary winding to the secondary winding and to diminish losses of the transformer.

The insulating body 20 is provided with a flange 26 surrounding the entire body and formed a little above the surface 22 of the insulating body 20.

The insulating body 21 is provided with a similar flange 27, which surrounds the entire insulating body 21 and which is situated somewhat below the surface 23 of the insulating body 21. Metallic sheets 27f are diagrammatically designated by broken lines in Figure 1 and are firmly connected to the adjacent surfaces of the insulating bodies 20 and 21 which carry these metallic sheets. The metallic sheets 27f are electrically connected with the iron core 14 as indicated by the reference character 27b in Figure 1.

Since the tube 12 is situated within the hollow insulating body 20, the primary winding 11 carried by the tube 12 is also situated within the body 20.

The secondary winding 19 is situated within the insulating body 21 since it is carried by the tube 18 which is situated within that insulating body.

Due to the described arrangement, a two-stage current transformer is formed which has the form of a compact column and which is very firm and stable in construction, although it occupies a comparatively small space.

The transformer illustrated in Figure 2 of the drawings comprises insulating bodies which are substantially similar to the insulating bodies shown in Figure 1. The characteristic feature of the transformer shown in Figure 1 is that it is formed by two insulating bodies placed one on top of the other. The characteristic feature of the transformer shown in Figure 2 is that it is formed by two insulating bodies, the adjacent walls of which have been united by baking or a similar process. Due to this baking, the transformer shown in Figure 2 comprises a single insulating body having an upper hollow portion 20a, the outer surface of which is provided with an annular flange 26a. The lower portion of the hollow insulating body is designated by the reference character 21a in Figure 2, and is provided with an annular flange 27a.

The interior of the hollow insulating body shown in Figure 2 is provided with several partition walls. A flat partition wall 22a is firmly attached to the upper portion 20a of the insulating body and is connected by a ridge 50 with two parallel flat partition walls 51 and 52. A hollow tube 18a is also situated within the insulating body and has one end which is firmly joined to the portions 20a and 21a of the insulating body. The opposite end of the tube 18a is firmly connected with the partition wall 51 and with another partition wall 51a, which is situated directly underneath the partition wall 51.

Another tube 12a is also situated within the hollow insulating body and constitutes a continuation of the tube 18a. One end of the tube 12a is firmly connected to the portions 20a and 21a of the insulating body while the other end of the tube 12a is connected to the partition wall 52 and to another partition wall 52a which is joined by the ridge 50a to the partition wall 51a. Another flat partition wall 23a is joined

to the portion 21a and to the wall 51a of the insulating body.

The primary winding 11a of the transformer is wound around the inner tube 12a. The secondary winding 18a of the transformer is wound around the tube 18a. An iron core 14a is situated within the tubes 18a and 12a. The iron core 14a carries a winding 15a which is entirely separate from all other windings and the two ends of which are connected with each other. This transformer operates in substantially the same manner as that illustrated in Figure 1.

The transformer shown in Figure 3 comprises an upper insulating body 28b which is similar in form to the insulating body 28 shown in Figure 1.

The insulating body 28 is hollow and is provided with an upwardly extending hollow portion 64 containing a single tube 61 which extends horizontally across the entire transformer. The tube 61 has a laterally extending portion forming a tube 62 which is concentric with respect to the tube 61 and encloses a portion thereof. The insulating body 28b has a downwardly extending hollow portion 65 provided with a hollow tube 63 fitting over the tube 62 of the body 28. The tube 63 is concentric in relation to the tube 62 when the transformer is assembled.

The tube 61 serves as a carrier for the secondary winding 19b which is wound around the tube 61 and the ends of which are shown in the drawings as being connected to a measuring instrument.

The primary winding 11b is wound in coils which are wound around the tube 63. Due to this arrangement, the primary winding 11b is concentrical in relation to the major portion of the secondary winding 19b. The transformer losses are considerably diminished due to this construction.

The transformer illustrated in Figure 4 comprises an insulating body 29 which is adapted to be placed over the insulating body 37. The insulating body 29 comprises a horizontal partition wall 30 which, when the transformer is assembled, is situated above the partition wall 31 forming a part of the insulating body 37. Another horizontal partition wall 32 is situated in the same plane as the partition wall 30 and is attached to the opposite side of the insulating body 29. A third partition wall 33 of the insulating body 29 is situated much higher than the partition walls 30 and 32, and is connected by vertical side walls 34 and 35 with them. A tube 36 is situated within the insulating body 29 and is connected to the partition wall 34 and to an outer wall of the insulating body 29.

Another tube 38 is also situated within the insulating body 29 and is substantially in alignment with the tube 36. The ends of the tube 38 are connected to the opposite outer wall of the insulating body 29 and to the partition wall 35.

The lower insulating body 37 comprises vertical side walls 39 and 40 which are situated opposite the walls 34 and 35 respectively. The wall 41 of the lower insulating body 37 is situated opposite the wall 33 while the wall 42 is situated opposite the wall 32. A tube 43 is situated within the lower insulating body 37 and its ends are connected with the vertical side walls 39 and 40 respectively. The tube 43 is in alignment with the tubes 36 and 38 so that all these tubes have a common central axis.

The primary winding of the transformer shown in Figure 4 consists of two coils 11c and 11d which are connected in series by the wire 11e. The coil 11c is wound around the tube 36 while the coil 11d is wound around the tube 38.

The secondary winding of the transformer is formed by the coil 19c which is wound around the tube 43 of the lower insulating body 31.

The transformer illustrated in Figures 5 and 6 of the drawings comprises an insulating body 70 which is hollow and which carries an inner rectangular tube 71. The lower end of the insulating body 70 is formed by parallel horizontal partition walls 72 and 73 which are interconnected by the vertical partition wall 74. The tube 71 carries the primary winding 75 which is wound around the tube 71.

The lower insulating body 76 which carries the upper insulating body 70, comprises an inner tube 77 which is in alignment with the tube 71. The tube 77 carries the secondary winding 78 of the transformer.

An iron core 79 is situated within the tubes 77 and 71 and is supported therein by any suitable means not shown in the drawings. The iron core 79 carries two coils 80 and 81 which are wound side by side upon the core 79 and the ends of which are connected in parallel with each other.

A bottle-like insulating body 82 is placed upon the upper insulating body 70 and serves as a closure for the insulating body 76. A conical hollow body 83 is situated within the interior of the lower insulating body 76 and is used for increasing the stability of the transformer. Sand 84 fills the interiors of the insulating bodies 82, 70 and 76.

As shown in Figure 5, the primary winding 75 is connected by wires 85 and 86 to a winding 87 which is wound around an iron core 88. Another separate winding 89 is wound concentrically around the winding 87 and its two ends are connected by wires 90 and 91 to terminals 92 and 93 respectively. Due to this arrangement, a two-stage transformer is formed which is comparatively low in height and very efficient in operation. It will be noted that in the transformer shown in Figure 5, there are two sets of windings which are inductively coupled, thereby forming a two-stage transformer; namely, the winding 89 is inductively coupled with the winding 87 and the winding 75 is inductively coupled with the winding 78.

The transformer illustrated in Figure 7 of the drawings comprises an upper insulating body 100 which is provided with a tube 101, which is adapted to be placed on top of the lower insulating body 102 provided with a tube 103 which is in alignment with the tube 101. A third insulating body 104 is placed on top of the insulating body 100 and is provided with an inner tube 105.

The tube 101 carries the primary winding 106 which is connected by wires 107 and 108 with the winding 109 carried by the tube 105. An iron core 110 is situated within the tube 105 and carries a winding 111, the two ends of which are connected to terminals 112 and 113 adapted to be connected to any suitable source of electrical energy. The tube 103 carries the secondary winding 114 which is wound around the tube 103.

In operation, the terminals 112 and 113 are joined to the source of electrical energy, so that an alternating current passes through the winding 111. This alternating current induces an alternating current in the winding 109 which sur-

rounds the winding 111 and is entirely separate therefrom. The current induced in the winding 109 is transmitted by the wires 107 and 108 to the winding 106. The winding 106, through the medium of the separate short-circuited winding 115 induces an electrical current in the secondary winding 114.

The transformer shown in Figure 8 of the drawings comprises an upper insulating body 117 provided with a tube 118 and adapted to be placed upon the lower insulating body 119 which carries the tube 120. A cylindrical top portion 121 is placed upon the insulating body 117.

The tube 118 carries the primary winding 122 while the tube 120 carries the secondary winding 123. Wires 124 and 125 are connected to the two ends of the primary winding 122. The wire 124 is connected to one of the terminals of a source of electrical energy. The wire 125 is connected to a switch 126 which is connected to the other terminal of the same source. The switch 126 is used for interrupting the connection between the primary winding 122 and the source of electrical energy which is not shown in the drawings.

I claim:—

1. In a current transformer, a lower insulating body, an upper insulating body carried by said lower insulating body, an insulating tube carried by said lower insulating body, an insulating tube carried by said upper insulating body, said insulating tubes being situated end to end and in alignment in relation to each other, one of said tubes forming a continuation of the other tube, the common central axis of said tubes being substantially transverse to the axis of said insulating bodies, a primary winding carried by one of said tubes, and a secondary winding carried by the other one of said tubes.

2. In a current transformer, a lower insulating body having a projecting portion, an upper insulating body carried by said lower insulating body and having a projecting portion fitting adjacent the first-mentioned projecting portion, an insulating tube carried by the first-mentioned projecting portion, another insulating tube carried by the second-mentioned projecting portion, said insulating tubes having the same diameter and being situated end to end and in alignment in relation to each other, one of said tubes forming a continuation of the other tube, the common central axis of said tubes being substantially transverse to the axis of said insulating bodies, a primary winding carried by one of said tubes, and a secondary winding carried by the other one of said tubes, and an iron core situated within said tubes.

3. In a current transformer, a lower insulating body having a projecting portion, an upper insulating body carried by said lower insulating body and having a projecting portion fitting adjacent the first-mentioned projecting portion, an insulating tube carried by the first-mentioned projecting portion, another insulating tube carried by the second-mentioned projecting portion, said insulating tubes having the same diameter and being situated end to end and in alignment in relation to each other, one of said tubes forming a continuation of the other tube, the common central axis of said tubes being substantially transverse to the axis of said insulating bodies, a primary winding carried by one of said tubes, a secondary winding carried by the other one of said tubes, and insulating partition walls interconnecting said tubes.

4. In a current transformer, two insulating bodies, one of said insulating bodies being carried by the other insulating body, one of said insulating bodies having two projecting portions, the other one of said insulating bodies having a projecting portion fitting between the two first-mentioned projecting portions, insulating tubes carried by said projecting portions, said insulating tubes having the same diameter and being

situated end to end and in alignment in relation to each other, one of said tubes forming a continuation of the other tube, the common central axis of said tubes being substantially transverse to the axis of said insulating bodies, and primary and secondary windings carried by separate insulating tubes.

FRANZ JOSEPH FISCHER.
